UNITED STATES PATENT OFFICE.

CHARLES H. INGERSOLL, OF CHICAGO, ILLINOIS.

NASAL DOUCHE.

SPECIFICATION forming part of Letters Patent No. 633,846, dated September 26, 1899.

Application filed May 3, 1899. Serial No. 715,487. (No model.)

To all whom it may concern:

Be it known that I, CHARLES H. INGERSOLL, of Chicago, in the county of Cook and State of Illinois, have invented certain new and useful Improvements in Nasal Douches; and I hereby declare that the following is a full, clear, and exact description thereof, reference being had to the accompanying drawings, which form part of this specification.

10 This invention is an improved douche-in-sufflato or powder-blower for the administration of medicaments, especially designed for use in treating diseases of the nose and throat by frequently applying medicine to the cavities in a very fine state of division. The device may be easily carried on the person without inconvenience, as the chamber containing the powder can be telescoped into the compressible bulb or bellows, which also acts 15 as a protective casing and prevents the breaking of the glass tube or chamber.

The invention consists in the novel construction and combination of parts hereinabove described and claimed, and illustrated in 20 the accompanying drawings, in which—

Figure 1 is an enlarged view of the douche as closed or folded for transportation in the pocket. Fig. 2 is a similar view of the same distended for use.

25 30 A designates a tube, preferably of glass, which is closed at one end by cap A', provided with an air-inlet aperture a, closed by a valve B, which is of suitable construction to permit the entrance of air. The other end 35 of the tube is closed by a cap C, provided with a cork C' and with a metallic nasal point C², an exit-opening a' being formed through the point, head, and cork, as shown.

35 Loosely fitted to the tube A and adapted to 40 telescope thereon is a compressible bulb D, which is closed at its rear end, but provided with an inlet-valve d, which will admit air, but prevent its escape therefrom. The other end of the bulb is provided with a large opening, through which the head A' of tube A is 45 inserted, and the end of the bulb fits tightly against the tube A, forming a substantially air-tight joint therewith. The bulb D is preferably of rubber, and of sufficient diameter, 50 size, and length to permit the tube A to be telescoped thereinto, as shown in Fig. 1. In this position the bulb forms a protective cas-

ing for the tube, as is evident, and by thus telescoping the parts together the size of the douche is reduced so that it can be conveniently carried in the pocket. When the bulb is drawn off the cylinder, as shown in Fig. 2, it can be compressed, as indicated by dotted lines D², so as to force air from the bulb into the tube A, wherein the medicament is placed. 55 This medicament may be of any suitable kind, and I propose to employ a finely-pulverized powder, which will be ejected through the nasal point C².

The air enters the bulb through the air-valve d. It is forced through the valve B into the tube and causes a great commotion in the very light powder contained in the tube and forces it out of the tube through point C², distributing it in the form of a fine cloud in 60 every part of the nasal cavity.

In some cases I may wish to employ the partition E and the bent pipe F. This partition may be made of cork and is tightly fitted in the tube A. One end of the pipe F opens through 75 the partition E. The other end extends forward, but is bent backward, so that the air entering the tube is blown back toward the partition. This will create a violent agitation of the air and powder, &c., in the tube. 80

If desired, when the partition is employed one medicament may be placed between the partition E and the head A' and another medicament placed between the partition and the nasal point, so that double medicaments 85 may be administered simultaneously, while they are normally separated from each other. However, I do not wish to limit myself to the employment of two medicaments or to the use of the partition and crooked tube. 90

The operation of the device is sufficiently obvious from the foregoing.

While I have described the device as quite small and adapted for a nasal douche, it, of course, may be made larger for other purposes. 95

Having thus described my invention, what I therefore claim as new is—

1. In a douche, the combination of the medicament-holding tube having a valved air-inlet and an air-outlet, with an air-forcing bulb surrounding the tube and adapted to telescope thereover, to form a protective casing therefor when not in use, and means for re-

taining the bulb upon the tube when it is withdrawn into operative position.

2. In a douche, the combination of the tube having a removable head provided with a 5 nasal point at one end and a valved air-inlet at the other end, a compressible bulb telescoping with the tube and adapted to entirely inclose the latter and form a protective casing therefor when not in use, and means for retaining the bulb upon the tube when it is withdrawn into operative position.

3. In a douche, the combination of the medicament-holding tube having a valved air-inlet and an air-outlet, a compressible bulb connected to the tube and adapted to telescope thereover, to form a protective casing therefor when not in use, a partition within said tube and a bent pipe therein connected to said partition.

20 4. In a nasal douche, the combination of the tube provided with a nasal point on one end and an air-inlet at its other end and a com-

pressible bulb connected to and adapted to telescope over the tube; with a removable partition in said cylinder and a bent pipe attached to said partition, for the purpose and substantially as described.

5. In a nasal douche, the combination of the tube having a removable head provided with a nasal point, and a fixed head provided with an air-inlet valve, and a compressible bulb connected to and adapted to telescope over the tube and provided with a valved air-inlet in its outer end; with a removable partition in said tube and a bent pipe attached to said partition within the tube, for the purpose and substantially as described.

In testimony that I claim the foregoing as my own I affix my signature in presence of two witnesses.

CHARLES H. INGERSOLL.
